Primary Examiner — Robert M Spear*Assistant Examiner* — Keith Frank(57) **CLAIM**

The ornamental design for a package for consumable product, as shown and described.

DESCRIPTION

FIG. 1 is a right perspective view of a package for consumable product showing our new design;

FIG. 2 is a front elevation view of FIG. 1;

FIG. 3 is a rear elevation view of FIG. 1;

FIG. 4 is a right side elevation view of FIG. 1;

FIG. 5 is a left side elevation view of FIG. 1;

FIG. 6 is a top plan view of FIG. 1;

FIG. 7 is a bottom plan view of FIG. 1;

FIG. 8 is a right perspective view of a package for consumable product showing our new design wherein the cover is in an open position;

FIG. 9 is a front elevation view of FIG. 8;

FIG. 10 is a rear elevation view of FIG. 8;

FIG. 11 is a right side elevation view of FIG. 8;

FIG. 12 is a left side elevation view of FIG. 8;

FIG. 13 is a top plan view of FIG. 8; and,

FIG. 14 is a bottom plan view of FIG. 8.
